SAFETY RAZOR

Jean-Baptiste Raoul Savary, Paris, France

Application August 23, 1937, Serial No. 160,390
In France April 7, 1937

14 Claims. (Cl. 30—83)

The present invention has for its object improvements in safety razors of the type in which the blade is held in its mean region between the cap and a guard or other seating part.

5 In the known safety razors the distance between the cutting edges of the blade and the guard remains constant. According to the invention it is possible to modify or adjust said distance as a function of the width of the blade.

10 For this purpose the invention is mainly characterized in that the position of the planes which are tangential to the cap and to the guard can be progressively and very accurately modified in such a manner as to cause to vary both the slope 15 of the cutting edges of the blade relatively to said planes and the extent of the projections which the cutting edges of the blades make on said planes.

The modification of said tangential planes is 20 effected by a displacement of the cap or of the guard, or, again, of the edges of this latter.

In an embodiment the seating member can carry adjustable marginal elements forming the guard or, again, it can be combined with a part 25 carrying the said elements.

The adjustable elements forming the guard can be displaced separately or simultaneously so as to enable, in the first case, different adjustments for the two cutting edges to be obtained on the 30 same razor.

The adjustable elements can be of any type, they can be formed by eccentrics or cams which are movable by rotation, or, again, by sliding parts.

35 The control means of the adjustable elements can also be of any desired type.

In another embodiment the edges of the guard are formed by resiliently deformable blades of which the position can be adjusted.

40 The cap can also be constructed with adjustable edges for the purpose hereinbefore indicated.

In another embodiment a block of resiliently deformable material such as rubber, which can be more or less compressed, can be interposed between the guard or the seating member and the blade which is pressed against the cap.

The invention further covers other particular 50 points which will appear in the following text made with reference to the accompanying drawings which is given by way of example only and in which:

Fig. 1 is an elevation in axial section of a safety razor constructed according to the invention, said section being taken along the line I—I of Fig. 2.

Fig. 2 is a side view corresponding to the previous figure.

Fig. 3 is a plan corresponding to Fig. 1 with a partial section taken along the line III—III of Fig. 1.

Fig. 4 is a side view, in partial section, of a modification of construction.

Fig. 5 is a side view, in partial section, of another form of construction.

Fig. 6 is a partial view in section taken along 10 the line VI—VI of the previous figure.

Fig. 7 is a transverse section of a modification of construction of a movable element forming a guard, said section being taken along the line 15 VII—VII of Fig. 8.

Fig. 8 is a section taken along the line VIII—VIII of the previous figure.

Fig. 9 is an embodiment, with partial sections, showing a device ensuring the watertightness of the inside of the rotating element forming a 20 guard.

Fig. 10 shows a device having an external cursor for controlling the rotating element.

Figs. 11 and 12 are transverse sections of 25 rotating elements.

Figs. 13—20 illustrate other embodiments of razors constructed according to the invention.

Fig. 21 is a side view of another embodiment.

Fig. 22 is a plan in section along the line 30 XXII—XXII of the previous figure.

Fig. 23 is a partial view of a modification of the construction illustrated in Figures 21 and 22.

The razor more particularly shown in Figs. 1, 2 and 3, comprises a cap 1, a seating member 2, a support 3 for the guards and a handle 4 at the 35 end of which is screwed a threaded head 5 secured to the cap.

The blade 6 is clamped in its mean longitudinal region, between the cap 1 and the seating member 2, the support 3 being held in an adjustable manner by screws 7 on the end lugs 2a of the seating member 2.

According to a particularly important point of the present invention, the guards of the razor are formed in the example of Figs. 1, 2 and 3 by 45 eccentric rollers 8. Said rollers are constructed with a longitudinal eccentric bore in which are engaged, on the one hand a longitudinal slit tube 9 for the passage of the operative end of a cursor 10, and on the other hand a threaded shaft 11 on 50 which is mounted the said cursor. The latter engages with its operative end in a helical or like groove 14 provided in the bore of the roller 8. The slit tube 9 is rigidly fixed to the support 3, and the shaft 11 terminates at its ends by operat-

ing knobs 15. By acting on the knobs 15, the shafts 11 are displaced in rotation and consequently the cursors 10 which are mounted on said shafts are displaced in translation, thereby causing an angular adjustment of the eccentric rollers 8 forming the guards of the razor. In a modification of construction of the device illustrated in Figs. 1, 2 and 3, the groove of the roller can be longitudinal, the groove of the tube being 10 in that case helical.

In the previously described razor, the two rollers 8 can be adjusted independently of each other, the adjustments shown being different in Fig. 2.

15 In said figure the planes P_1 and P_2 , which are tangential respectively to the cap 1 and to the rollers 8, subtend with the line I—I different angles α_1 and α_2 . The adjustment of the eccentric rollers enables the value of the projections formed by the cutting edges of the blade on said planes, to be modified relatively to the planes P_1 and P_2 , as well as the angles which said cutting edges subtend with said planes.

Fig. 4 illustrates a modification of construction 25 of the first form described. The eccentric rollers 8 are rotatably mounted direct on the shafts 11 and are locked in position by nuts 18. This adjusting device by means of the direct action on the rollers 8 is a very simple construction.

30 Fig. 5 illustrates another construction in which the previously described tube is eliminated, the rotating elements 8 which form the guards having the shape of cams. The axis of the cursor 10 is eccentric relatively to the axis of the cam 8. 35 The cursor slides on a threaded rod 11 and penetrates into a helical groove 14 of the element 8. It will be observed that the watertightness of the inside of the cam is ensured by locking this latter at its ends against its support.

40 Figs. 7 and 8 illustrate a modification of the construction of Fig. 5 the cursor 10 having two projections 10^a which engage in two helical grooves provided in the corresponding guard 8.

Fig. 9 shows a modification of construction in 45 which the ends of the guards 8 are closed by parts 20.

In the example of Fig. 10 the cursor is movable by translation on a rod 22 and engages in a groove 14 provided in the periphery of the 50 guard 8.

Figs. 11 and 12 illustrate two other forms of construction of control-means of a guard 8. Fig. 11 is a modification of the guard of the razor illustrated in Figs. 1 and 2, the same members being indicated by the same references as in 55 said figures.

In the example of Fig. 12 the cursor 10 is held 60 stationary angularly by a semi-cylindrical fixed rod 25, said cursor being displaced by the threaded rod 11.

The inside of the guard carries a helical groove, the fixed rod which is in principle semi-cylindrical having a plane face passing through its axis or parallel to the latter. In a modification of 65 this arrangement the fixed rod 25 can have a helical surface instead of a plane surface, the groove of the guard being straight.

Fig. 13 shows a razor in which the guards 8 are held stationary by screws 29. The guards 70 can again be held stationary by bolts formed in particular by resiliently deformable blades 30 (Fig. 14).

The hinged guards as illustrated in Fig. 15 can be simultaneously controlled by a common screw 35, the guards 8 and the screw 35 forming

a system of the worm and tangential wheel type.

In the example of Fig. 16 the hinged guards 8 have arms 36 which are displaced by screws 37 against the action of springs or blocks of rubber.

Fig. 17 illustrates a modification of construction of Fig. 15; the guards forming tangential wheels are driven by different worms 35^a and 35^b.

Figs. 18 and 19 illustrate a device for locking the guards through the instrumentality of radial notches 47.

In the example of Fig. 20 the guards 8 have toothed segments 48 with which engages a resilient locking blade, 49.

Figs. 21 and 22 illustrate an embodiment of a 15 razor of a simple construction and of which the adjustment can be effected with very great accuracy.

Each guard 8 which is constructed in the shape of a tubular body is internally threaded to receive a screwed rod 53 of which the ends, forming trunnions 54, are eccentric relatively to the longitudinal axis of said rod 53.

The trunnions are engaged in corresponding 25 bearings provided in end supports 55, it being possible to subject each rod 53 to a slight axial 25 displacement relatively to the supports. The bodies 8 have tails 56 terminating in heads 57 engaged in corresponding grooves 58 provided in the supports 55.

By engaging a screwdriver, which can consist 30 of the lower removable end of the handle, in a saw cut provided in the end of each trunnion 54, each rod 53 and consequently the corresponding guard 8 can be angularly displaced. Two positions of the guards 8 are shown by way of indication in Fig. 21. The screw driver can be eliminated and replaced by two knobs 70 as partially shown in Fig. 23. In this case, the angular displacement of each rod 53 is obtained by the rotation of a knob operated with the finger. Each 40 knob is carried by the corresponding rod 53 and has its housing in a cavity provided in the corresponding guard 8. Each knob can have a striated portion permitting of the action of the finger as indicated at 71 and a smooth portion 72 45 on which are marked graduations intended to facilitate the adjustment of the guards by the user, a mark being provided at 73 for example. It will be observed, as illustrated in Fig. 23, that the rods 53 are smooth and that the corresponding bores provided in the guards 8 have no threads. Furthermore, means are provided for locking each cam in any position of use.

It is obvious that the embodiments described and illustrated are only given herein by way of 55 indication and are non-limitative. Any modifications or variations which in no way alter the main characteristics hereinbefore explained or the object aimed at, remain included in the scope of the present invention.

I claim:

1. In a safety razor in which the blade is held, in its medial region, between a cap and a seating member, in combination: a support, rollers eccentrically pivoted on said support to progressively and very accurately modify the position of the planes which are tangential to the cap and to the guards, so as to simultaneously vary the slope of the cutting edges of the blades relatively to said planes and the amount by which the cutting edges of the blades project from said planes.

2. In a safety razor as claimed in claim 1, the said rollers are provided with a longitudinal eccentric bore in which are engaged, on the one hand a longitudinally slit tube, and the other

hand a threaded shaft on which is mounted a cursor having an operative end engaged in a helical groove provided in the bore of the corresponding roller, means being provided for rigidly fixing the slit tube to said support, and the threaded shaft is shaped at its ends to form operating knobs.

3. In a safety razor as claimed in claim 1, the said rollers are provided with a longitudinal eccentric bore in which are engaged, on the one hand a helically slit tube, and on the other hand a threaded shaft on which is mounted a cursor having an operative end engaged in a longitudinal groove provided in the bore of the corresponding roller, means being provided for rigidly fixing the slit tube to the said support, and the shaft is shaped at its ends to form operating knobs.

4. In a safety razor as claimed in claim 1, each roller is provided with an eccentric bore for the passage of a shaft mounted on the said support, means being provided for locking each roller in any desired position on the support.

5. In a safety razor in which the blade is held, in its medial region, between a cap and a seating member, in combination: a support, two elements forming guards and rotatably mounted on said support, each element being constructed as a cam with a longitudinal bore and a helical groove, a cursor engaged in each bore and constructed with a nose engaged in the corresponding helical groove, each cursor being constructed with a tapped eccentric perforation, a threaded rod for each cursor, each threaded rod being engaged in the tapping of the corresponding cursor and rotatably mounted, so that the rotation of each rod produces only a translation of the corresponding cursor and consequently a rotation of the corresponding cam element.

6. In a safety razor as claimed in claim 5, a second helical groove in each rotating cam element and a second projection on the cursor to engage in said second helical groove.

7. In a safety razor in which the blade is held, in its medial region, between a cap and a seating member, in combination: a support, two guard elements rotatably mounted on said support, each element being constructed as a cam with a helical groove, a cursor provided with a nose engaged in the groove, each cursor being provided with a tapped perforation, a threaded rod for each cursor, each threaded rod being engaged in the tapping of the corresponding cursor and rotatably mounted so that the rotation of each rod produces only a translation of the corresponding cursor and consequently a rotation of the corresponding cam element.

8. In a safety razor in which the blade is held, in its medial region, between a cap and a seating member, in combination: a support, two guard elements rotatably mounted on said support and each provided with an axial bore and a helical groove, two tubes, each provided with a longitudinal slit, each of said tubes being engaged in the bore of the corresponding element and rigidly fixed to the support, two cursors, each engaged in the corresponding tube, the longitudinal slit of said tube and the corresponding groove of the cam element, each cursor being provided with a tapped hole, two threaded rods adapted to rotate in said support, each rod being engaged in the tapped hole of the corresponding cursor so that the rotation of each rod causes a translation of the corresponding cursor and consequently a rotation of the corresponding guard element.

9. In a safety razor in which the blade is held,

in its medial region, between a cap and a seating member, in combination: a support, two guard elements rotatably mounted on said support and each provided with an axial bore and a helical groove, two semi-cylindrical rods engaged in the two bores of the guard elements, two semi-cylindrical cursors having a projection, each cursor being engaged in the cut away portion of the bore of the corresponding cam element, said projection being engaged in the corresponding helical groove, each cursor having a tapping, two threaded rods adapted to rotate in said support, each rod being engaged in the tapping of the corresponding cursor so that the rotation of each rod causes a translation of the corresponding cursor and consequently a rotation of the corresponding guard element.

10. In a safety razor in which the blade is held, in its medial region, between a cap and a seating member, in combination: a support, parts forming guards rotatably mounted on said support and constructed as cams and having an arcuate toothed portion, and a worm meshing with said arcuate parts, so that the rotation of said worm causes the rotation of the parts forming guards.

11. In a safety razor in which the blade is held, in its medial region, between a cap and a seating member, in combination: a support, parts forming guards rotatably mounted on said support and constructed as cams and having an arcuate toothed portion and two worms one meshing with the toothed portion of one of the guards and the other with the toothed portion of the other guard, so that the rotation of each worm causes the rotation of the corresponding cam-forming part.

12. In a safety razor in which the blade is held, in its medial region, between a cap and a seating member, in combination: a support, guards rotatably mounted on said support and constructed as cams, toothed segments secured to said guard and resilient blades engaged in the toothings of said segments to resiliently lock the latter in position and consequently the said guards, while permitting rotation of said guards.

13. In a safety razor in which the blade is held, in its medial region, between a cap and a seating member, in combination: a support having bearings and grooves, threaded rods having eccentric ends forming trunnions and engaged in said bearings, and guards constructed as cams and having a longitudinal axial tapped bore for receiving the threads of said rods, said guards furthermore having a lever arm terminating in a head engaged in a corresponding groove of the support so that the rotation of the threaded rods causes an eccentric rotation of said guards.

14. In a safety razor in which the blade is held, in its medial region, between a cap and a seating member, in combination: a support having bearing portions and grooves, smooth cylindrical rods having eccentric ends forming trunnions and engaged in said bearing portions and guards constructed as cams and having a longitudinal axial bore to receive said rods, said guards furthermore having a lever arm terminating in a head engaged in a corresponding groove of the support, so that the rotation of the rods produces an eccentric rotation of said guards which are furthermore shaped to each form a cavity to accommodate a knob which is secured to the corresponding rod and which is adapted to be actuated with the finger to displace said rod and consequently the corresponding guard, and means for locking said guards.
